By Herbert E. Smith

Attorney

UNITED STATES PATENT OFFICE.

FRANKLIN W. GIBSON, OF SEATTLE, WASHINGTON.

SKIVING MACHINE.

Application filed December 5, 1927. Serial No. 237,618.

My present invention relates to an improved skiving machine which while adapted for various uses is especially and particularly designed for use in a shoe 5 pair shop and is of the hand-operated type.

The invention consists in certain improvements in the combination and arrangement of the feed rollers and the skiving knife and in improvements in the knife itself with regard to its adjustment. Means are provided whereby the feed rollers are capable of adjustment to accommodate various thicknesses of leather soles, and means are also provided whereby the knife may be 15 adjusted with relation to the feed rollers in order to accomplish the cutting of the bevel on the shoe sole at various angles.

The invention consists in certain novel combinations and arrangements of parts as 20 will hereinafter be more fully set forth and claimed.

In the accompanying drawings I have illustrated one complete example of the physical embodiment of my invention 25 wherein the parts are combined and arranged according to the best mode I have so far devised for the practical application of the principles of my invention.

Figure 1 is a view in rear elevation of a 30 well known type of skiving machine having the improvements of my invention installed thereon.

Figure 2 is an enlarged end view showing 35 the operating parts of the machine.

Fig. 3 is a vertical sectional view at line 3—3 of Fig. 1.

Fig. 4 is a top plan view showing the 40 knife and its adjustable support in relation to the feed rollers.

Fig. 5 is an enlarged detail sectional view at line 5—5, Fig. 4, showing the eccentric means for angularly adjusting the blade of the knife.

Fig. 6 is an enlarged detail sectional view 45 at line 6—6 of Fig. 2.

Fig. 7 is a perspective view showing the eccentric support by means of which the knife is angularly adjusted.

Fig. 8 is a perspective view showing a 50 shoe sole with the tapered or beveled rear edge that is cut by the skiving machine.

In order that the general arrangement and relation of parts may readily be understood I have shown in Fig. 1 a well known type 55 of leather cutting machine comprising the

main frame 1 which is provided with a fixed cutting table 2 and the cutters 3 and 4 adjacent to the table which are used for cutting shoe soles, in usual manner.

The shoe soles after being fashioned or cut to shape are given a taper or bevel as indicated in Fig. 8 where the sole is designated S and the bevel B.

The sole S is fed to the knife which cuts the bevel through a pair of feed rollers 5 and 7, the former having a shaft 6 with a fixed bearing in the main frame, and the lower roller 7, which is corrugated, is provided with a shaft 8 that is journaled in the adjustable frame 9. A train of gears 10 is 60 indicated in dotted lines in Fig. 1 in the gear casing 11 and a hand crank 12 is used to operate the rollers through the train of gears and their shafts.

The lower corrugated feed roller 7 is adjustable with relation to its complementary roller for the purpose of accommodating various thicknesses of shoe soles as designed for men's and women's shoes. The frame 9 of the lower roller is provided with a vertically disposed stud 13 which is movable in the bearing boss 14 of the frame 1.

Below the stud a spring 15 is interposed between the head 16 on the stud and a head 17 on the bolt 18 which is threaded in the lug 19 of the frame. These parts are alined or centered and the bolt 18 is used to vary the tension of the spring 15 and it will be apparent that the latter tends to urge the frame and its lower roller upwardly at all times. The 70 frame 9 may be lowered in order to move the lower roller away from the upper roller for a thicker piece of leather through the operation of a cam lever 20 which is located in position where it is readily accessible for the operator of the machine. This cam lever is pivoted on a bolt 21 which is screwed into the frame 9 and loosely passes through a lug on the main frame or rather on the boss 14 of this frame. The bolt is provided with 75

a head 22 and a cam block or washer 23 is supported above the bolt head and provided with a guide face 24 for coaction with the periphery of the boss 14 to hold this cam block in proper position. The cam block on its upper face is provided with cams 25 and the head of the cam lever is interposed between these cam faces and the underside of the lug 14' of the boss 14. Thus it will be 80

apparent that when the lever is turned to the 85

different dotted line positions in Fig. 6, due to the cam action, the frame which supports the lower roller may be depressed against the tension of the spring 15, for the purpose of holding the lower roller in spaced adjustment from the upper roller.

The feed rollers of course are designed to feed the shoe sole to the horizontally disposed knife 26 which is retained in its frame 27 by means of the screws 28. This frame is supported in such manner that it may be adjusted angularly for the purpose of changing or varying the relation of the knife to the feed rollers to vary the bevel or tapered cut on the shoe sole as indicated at B in Fig. 8.

At one side the knife frame 27 is pivoted on a screw 29 which is threaded into a link 30 of the main frame. This screw may be tightened to clamp the frame in rigid position and it may be loosened to permit swinging of the frame on the bolt or screw as a center for accomplishing the angular adjustment of the knife.

At the opposite side of the knife frame is provided an enlarged cylindrical sleeve 31 in which is encased an eccentric 32 and this eccentric has a head 33 with a gauge on its exterior face and an exterior handle 34 on the head may be used to turn the eccentric 32 within the sleeve 31. A bolt 35 passes through the head and the eccentric and is threaded into a part of the main frame 1 of the machine. This bolt has a head 36 and handles 37 thereon, and it will be apparent that when the bolt 29 has been loosened, by turning the head 36 the bolt 35 may be loosened in its main frame 1. Then by turning the head 33 of the eccentric, the latter

may be turned within the sleeve 31 and as the bolt 35 is located eccentrically to the longitudinal center or axial center of the eccentric 32 it will be apparent that the sleeve 31 and frame 27 will be raised or lowered depending upon which way the eccentric is turned. After the eccentric has been turned to desired position the head 36 is turned by grasping the handles 37 and then the eccentric and the sleeve 31 are rigidly clamped against the main frame and of course the knife frame and knife are held thus in rigid position.

Having thus fully described my invention what I claim as new and desire to secure by Letters Patent is:

1. The combination in a leather working machine with its main frame and upper roller of a movable frame and its lower roller, a stud on the movable frame supported in the main frame and a tension spring below said stud, a bolt threaded to the movable frame and supported in the main frame, a cam block on the bolt, and a cam lever on said bolt for coaction with the block.

2. The combination in a leather working machine with its main frame and feed rollers, of a knife frame, a screw for securing the knife frame to the main frame at one side of the knife, said knife frame having a sleeve at the other side of the knife, an eccentric in said sleeve, and a bolt fastened to the main frame and rotatably supporting the eccentric at the axis of rotation thereof.

In testimony whereof I affix my signature.

FRANKLIN W. GIBSON.
